UNITED STATES PATENT OFFICE.

HENRY W. BRITTON, OF STOUGHTON, MASSACHUSETTS.

BICYCLE.

SPECIFICATION forming part of Letters Patent No. 233,723, dated October 26, 1880.

Application filed August 26, 1880. (No model.)

To all whom it may concern:

Be it known that I, HENRY WILLIAMS BRITTON, of Stoughton, in the county of Norfolk and State of Massachusetts, have invented 5 a new and useful Improvement in Bicycles, of which the following is a specification.

Figure 1 is a side elevation of the improvement. Fig. 2 is a sectional side elevation of a part of the improvement enlarged, taken 10 through the line *xx*, Fig. 3. Fig. 3 is a rear elevation of a part of the improvement. Fig. 4 is a sectional plan view taken through the line *yy*, Fig. 3.

The object of this invention is to furnish 15 bicycles so constructed that the rider can adjust his seat to keep it in proper position over the large wheel when riding upon inclined ground.

Similar letters of reference indicate corresponding parts.

A represents the large wheel, and B the small wheel, of a bicycle. To the journals of the large wheel A are attached the cranks or foot-levers C. The journals of the large wheel 25 25 A revolve in bearings in the lower end of the standard D, which is slotted or forked to receive the upper part of the large wheel A. The journals of the small wheel B revolve in bearings in the forked rear end of the backbone or reach E.

The backbone E is curved upward and forward to pass over the upper part of the large wheel A. The forward part of the backbone E passes through an aperture in the standard 35 35 D, and to its forward end is hinged the forward end of an arm, F. The bar or arm F passes back above the forward end of the backbone E, and its rear end is notched, enters apertures in the upper part of the standard D, and has a vertical hole formed through its rear end, through which passes the screw G. The screw G is swiveled to the standard D by a set-screw, H, which enters a ring-groove in the screw G, or by any other suitable means. The screw G also passes through

a nut, I, inserted in a short slot in the backbone E.

The nut I is made in two parts, as shown in Figs. 2 and 3, so that its parts can be inserted from the opposite sides of the backbone E. 50 The parts of the nut I that enter the backbone E are flattened upon the opposite sides, to prevent it from turning in the slot of the backbone E.

To the upper end of the screw G is attached 55 a crank-wheel, J, for convenience in operating it.

To the backbone E, a little in the rear of the standard D, is attached the saddle K.

A spring, L, may be interposed between the 60 saddle K and the backbone E to give elasticity to the said saddle.

To the top of the standard D are attached the lever-handles M, by means of which the machine is guided. With this construction, 65 by turning the screw G the forward end of the backbone E will be raised or lowered to bring the small wheel B closer to or farther from the large wheel A, and thus keep the saddle K in its proper position over the wheel A. 70

Having thus described my invention, what I claim as new, and desire to secure by Letters Patent, is—

1. In a bicycle, the combination, with the standard D and the backbone E, of the swiveled screw G and the nut I, substantially as herein shown and described, whereby the backbone E can be adjusted to raise and lower the small wheel B, as set forth. 75

2. In a bicycle, the combination, with the standard D, the backbone E, the swiveled screw G, and the nut I, attached to the backbone E, of the hinged arm F, substantially as herein shown and described, to hold the backbone E in place, while allowing it to play upon 80 the nut I, as set forth. 85

HENRY WILLIAMS BRITTON.
